US0D1066483S

(12) **United States Design Patent** (10) Patent No.: **US D1,066,483 S**
(45) Date of Patent: ** Mar. 11, 2025

(54) **PRINTER**

(71) Applicant: **Canon Kabushiki Kaisha**, Tokyo (JP)

(72) Inventors: **Daijiro Nagasaki**, Kanagawa (JP);
Mudai Tanaka, Kanagawa (JP)

(73) Assignee: **Canon Kabushiki Kaisha**, Tokyo (JP)

(**) Term: **15 Years**

(21) Appl. No.: **29/880,756**

(22) Filed: **Jul. 27, 2023**

(30) **Foreign Application Priority Data**

Jan. 31, 2023 (JP) ..... 2023-001613 D

(51) **LOC (15) Cl.** **14-02**

(52) **U.S. Cl.**

USPC **D18/50**

(58) **Field of Classification Search**

(57) **CLAIM**

The ornamental design for a printer as shown and described.

DESCRIPTION

FIG. 1 is a front view of a printer with an open cover, showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof; and,

FIG. 8 is a perspective view showing the printer with closed cover.

The broken lines in the drawings illustrate portions of the printer which form no part of the claimed design.

1 Claim, 8 Drawing Sheets
